UNITED STATES PATENT OFFICE.

EDWARD M. McGOWAN, OF TOLEDO, OHIO.

POSTAGE-MARKING MACHINE.

1,389,062.

Specification of Letters Patent. Patented Aug. 30, 1921.

Application filed January 17, 1921. Serial No. 437,689.

To all whom it may concern:

Be it known that I, EDWARD M. McGOWAN, a citizen of the United States, and a resident of Toledo, in the county of Lucas and State of Ohio, have made an Invention Appertaining to Postage-Marking Machines; and I do hereby declare the following to be a full, clear, and exact description of the invention, such as will enable others skilled in the art to which it appertains to make and use the same, reference being had to the accompanying drawings, and to the characters of reference marked thereon, which forms a part of this specification.

15 My invention has for its object to provide a machine for marking a predetermined totaled amount of postage on mail for which the machine is set from time to time. The invention has for its object to provide 20 in such a machine a means whereby access to the setting means may be prevented except by those authorized to set the machine for the predetermined amount of postage to be marked by the machine. The invention 25 also provides certain indicating means that have utility in setting the machine and in the use of the machine.

The invention also has for its object to provide a simple and efficient construction 30 that may be conveniently handled and manipulated for the marking of the mail and for setting the machine to limit the operations of the machine to the marking of a predetermined amount of postage.

35 The invention may be contained in structures of different forms. To illustrate a practical application of the invention I have selected one of the structures containing the invention and shall describe it hereinafter. 40 The structure selected is illustrated in the accompanying drawings.

Figure 1 of the drawings illustrates a side view of the machine, the cover having been removed. Fig. 2 illustrates an end view 45 of the machine, the case containing the machine being shown in section. Fig. 3 is a top view of the machine, the case containing the machine also being shown in section. Fig. 4 is a diagrammatic view to show the 50 interrelation of parts of the machine. Fig. 5 illustrates a Swiss gear used in operating parts of the machine. Fig. 6 illustrates a part of an automatic release mechanism used in the machine. Fig. 7 illustrates the 55 actuating lever of the machine. Fig. 8 illustrates the stamping bar and the mark-

ing stamp. Fig. 9 illustrates a shifting actuating gear. Fig. 10 illustrates one of a number of rings that coat with the actuating gear shown in Fig. 9. Fig. 11 illustrates one of a number of ratchets used in the machine.

In Figs. 1, 2 and 3, 1 is a case having a base 2 for inclosing the postage marking machine. It is provided with a cover 3 that 60 may be locked by a suitable lock 4 to prevent alteration in the adjustment of the machine after it has been set for a predetermined amount of postage that the machine 65 is to mark until the machine has been reset 70 as by the postal officials having authority to set machines of the character shown in the drawings. The machine is supported on the base by means of a standard 5 which is provided with suitable bearings for the 75 moving parts of the mechanism. A rod 6 is supported in a bracket 7 and an arm 8. A plate 9 is secured to the bracket 7 and also to a ring 10 which is secured to the end of the rod by means of a screw 11. The rod 80 6 may be secured in the arm 8 as well as by the plate 9 to prevent rotation of the rod. The plate 9 is provided with openings 12. Below the plate 9 and the openings 12 are located a plurality of disks such as the disks 85 13, 14 and 15 which are rotatably supported by the rod 6. The periphery of the disks is provided with sequentially arranged numbers or other indicia that register with the openings 12 according to the relative location of the disks.

The disks 13, 14 and 15 are ratcheted to the ends of the sleeves 16, 17 and 18 respectively, in the manner shown in Fig. 11, and are arranged concentrically on the rod 6 95 and are supported in the bracket 7. The disks are connected to the sleeves by means of the spring pressed pins or dogs 19. The other ends of the sleeves are connected to the disks 20, 21 and 22 whereby rotation of 100 the disks 13, 14 and 15 will cause also rotation of the disks unless the disks 20, 21 and 22 are held, in which case the pins 19 will slip over the sleeves when the disks 13, 14 and 15 are rotated in one direction, but will 105 turn the disks 20, 21 and 22 if rotated. The disks 20, 21 and 22 are provided with lugs 23 that protrude from the disks. The lugs will take positions according to the numbers that appear through the openings 12 110 in the plate 9.

A gear wheel 24 is located on one or the

other of the disks 20, 21 and 22. It is provided with an opening that corresponds to the shape of the disks and the lugs 23 formed thereon. It also has a circular recess 25 for receiving the lug of the disk on which the wheel 24 is located without actuating the disk upon rotation of the wheel 24, the lug 23 of each of the disks being located on one side of the center of the outer surface or periphery of the disk. When, however, the wheel 24 is turned so that the opening 26 which has the same shape as the lugs 23 on the disks has reached a point so as to cause the two to register, the wheel 24 will 10 slip over the disk and onto the next disk, further forward movement being held by the lug of the succeeding disk until the wheel 24 has rotated sufficiently to cause registration between the lug 23 of that disk 15 with the opening 26, that has the same shape as the lug, whereupon the wheel 24 may be slipped onto the next disk in the same manner. The wheel 24 may thus, under certain conditions, be slipped over the disks 20, 21 20 and 22. Its sliding movements over the disks 20, 21 and 22 are thus controlled by the relative positions of the lugs of the disks 25 and the opening formed in the wheel 24.

The wheel 24 may be provided with a 30 gnarled ridge 27 for purposes of adjustment or manipulation of the gear wheel 24 relative to other parts of the mechanism.

The wheel 24 is slid over the lugs by means of the arm 28 which is slidably supported on the shaft 29. It is operated by the compression spring 30 which is located on the rod 31 and between the bracket 32 and the arm 28. The spring 30 is socketed in the bracket 32 and is located between the 35 bottom of the socket and the arm 28. The spring operates to push the arm 28 along the shaft 29 and to pull the rod 31 through the arm 32 of the bracket 7. The arm 28 is provided with rollers 33 that are pressed 40 against the surface of the gear wheel 24 by the operation of the spring 30 so that when the gear wheel 24 reaches a certain point in its rotation on one of the disks 20, 21 or 22 it will push the gear wheel 24 onto 45 the next disk or onto the dummy disk 34 which is provided with a flange 35 which will limit the forward movement of the gear wheel 24, and also the forward movement of the arm 28. If desired, the spring 30 may 50 be held compressed by the snap 36 which is pivoted on the bracket 32.

The gear wheel 24 meshes with one or the other of the gear wheels 38, 39 or 40, while the gear wheel 24 is riding on one of the 55 disks 20, 21 and 22. The gear wheel 38 is secured to a rod 41 while the gear wheels 39 and 40 are connected to the concentric sleeves 42 and 43 respectively which are located on the rod 41. The rod 41 and the sleeves 42 60 and 43 are supported in the arm 8 of the

standard 5, and the rod 41 is supported in the arm 57 of the standard 5. Gear wheels 44, 45 and 46 are connected to the rod 41 and the sleeves 42 and 43 respectively whereby rotation of any one or more of the 70 gear wheels 44, 45 and 46 will cause the same rotation in the gear wheels 38, 39 and 40.

Pin wheels 47 and 48 of a Swiss gear are connected to the gear wheels 45 and 46 and 75 the coacting mutilated gear wheels 49 and 50 of the Swiss gear are pivotally supported on the shaft 29. A gear wheel 52 is ratcheted to the shaft 29 by means of the disk 82, which is keyed to the shaft by the key 53, 80 and the spring pressed pin 54. The spring pressed pin 54 operates as a dog which is engaged by the disk 82 when the disk 82 and the shaft 29 is rotated in one direction. The disk 54, however, slips by the disk 82 85 and the ratchet formed thereon upon return movements of the shaft 29.

The gear wheel 52 meshes with the gear wheel 46 and causes rotation of the pin wheel 48 which operates upon the mutilated 90 Swiss gear wheel 49 to cause step by step rotation of the wheel 49 on the shaft 29. A gear wheel 55 is connected to the wheel 49 and meshes with the gear wheel 45 which is connected to the pin wheel 47. The pin 95 wheel 47 operates upon the Swiss gear wheel 50 to cause step by step movements in the gear wheel 50. A gear wheel 56 is connected to the Swiss gear wheel 50 and meshes with the gear wheel 44. The shaft 100 29 is supported in the arms 8, 32 and 57 that extend from the standard 5.

The shaft 29 is adjustably connected at one end to the sector 58 by means of the screw 59, and a lever 60 is supported on the 105 shaft 59 to cause rotative movements of the shaft 29 under certain conditions. A spring 100 operates to lift the lever 60. The lever 60 is preferably formed in two parts 101 and 102. Part 101 is located within the 110 case and part 102 extends through a slot to a point on the outside of the case, and so as to be operated by the finger of the operator. The part 102 may be easily separated from the part 101 since one end of the part 102 115 telescopes into the free end of the part 101, and the parts are yieldingly held in this relation by means of the spring 103 which presses against the upper edge of the part 102. The spring 100 is located between the 120 lever 60 and the bracket 104 which is secured to the side wall of the case. A stop 105 is also secured to the side wall of the case to limit the upward movement of the lever 60 caused by the operation of the 125 spring 100. The lever 60 is connected to the shaft so as to rotate the shaft by means of the sector 61 which is slip-keyed to the shaft by the key 90 except when the gear wheel 24 rides upon the dummy 34. The sector 61 130

130

is provided with a slot 62 through which the rod 31 extends. The rod 31 is provided with a flange or head 63 which engages the sector 61 when the gear wheel 24, which is moved by the arm 28 across the disks 20, 21 and 22, moves upon the disk or dummy 34. The sector 61 has a finger 64 that clutches with the lever 60, the lever 60 having a recess corresponding in shape to the finger 64 except that the recess is larger than the finger to permit engagement and disengagement between the sector 61 and the lever 60. This engagement occurs when the arm 28 slides upon the disk or dummy 34, and in the return movement of the lever 60. The sector 61 has a recess 98 into which the head 63 of the pin 31 will enter under the pressure of the spring 30 which holds the sector 61 down while the lever 60 returns by the pressure of the spring 100. This causes disengagement of the clutch since the finger 64 will be released from the lever 60. Engagement may be established by shifting the gear wheel 24 so that it will ride upon one of the disks 20, 21 and 22. This occurs when the pin 31 is drawn back so as to remove the flange 63 from the sector 61.

Movements of the lever 60 are communicated to the sector 58. The sector 58 is connected to a reciprocating rod 67 by means of a steel band 68. The rod 67 is spring pressed by means of the spring 69 located in a sleeve 70 and between the bottom of the sleeve and a shoulder 71 formed on the rod 67. The rod 67 may be channeled along a portion thereof as at 72, and rotation of the rod relative to the sleeve 70 may be prevented by means of the screw 73. The sleeve 70 is supported by an arm 88 extending from the standard 5. The end of the arm is slit so as to form a slit collar 86, and the bolt or nut 87 may be used to clamp the sleeve 70 within the collar 86, and thus adjustably position the sleeve relative to the base 2. A stamp 74 is connected to the lower end of the rod 67 and a stamping pad 75 may be supported on the lower end of the sleeve 70 by means of the bracket 76 which may be clamped to the sleeve 70. The pad 75 is pivotally connected through the arm 77 to the bracket 76, and a spring 78 operates to yieldingly press the pad 75 against the stamp 74 when the spring 69 has raised the rod 67 to its uppermost position in the sleeve 70. A roller 79 may be supported at the rear of the stamp 74 so as to push the pad 75 to one side when the stamp 74 is moved down toward the base 2. One of the sides of the case 1 is provided with a slot 80, while a portion of the lower edge of the cover 3 is raised slightly from the base 2. Mail may be inserted through the slot thus formed above the base and so as to be pressed in position to receive the marking of the stamp 74.

The wheels 44 to 48 inclusive may be secured to the disks 106 which are mounted on the ends of the sleeves 42 and 43 and the rod 41. Rings 85 may be ratcheted to the disks 106, and numbers may be placed on the rings 85. The rotations of the wheels 44 to 46 inclusive by the operations of the shaft 29 will thus be indicated by the location of the numbers relative to any fixed point that may be selected.

In the operation of the device the lever 60 actuates the shaft 29 which operates the sector 58 that moves the stamp 74 toward the base and marks the mail. Each time the shaft 29 is moved the angular distance permitted by the movement of the stamp 24 between the sleeve 70 and the mail on the base 2 it rotates the gear wheel 52 a short angular distance. The wheel 52 meshes with the wheel 46 and the pin wheel 48, being connected to the wheel 46, the pin wheel 48 is moved the same angular distance. However, upon the return movement of the shaft 29 the disk 82 slides beneath the pin 54 without causing return movement of the wheel 52. The rotation of the wheel 46 is continued by the movements of the lever 60 until the pin 83 engages the mutilated Swiss gear 49 to move it one step. This motion is communicated to the gear wheel 55 which is connected with the gear wheel 49, and also to the gear wheel 45 which meshes with the gear wheel 55. Also this motion is connected to the pin wheel 47. The step by step movements of the gear wheels 45 and 46 continue until the pin 83 (Fig. 3) of the pin wheel 47 engages a tooth of the Swiss gear 50, and this movement is communicated to the gear wheel 56 which meshes with the gear wheel 44. The gear wheel 44 is connected to the shaft 41 and the movement of the gear wheel 44 is also reproduced in the movement of the gear wheel 38 which operates upon the gear wheel 24. The gear wheel 24 is rotated until its recessed portion 26 registers with the lug 23 located on the disk 20 provided that the gear wheel 24 is located on the disk 20. When the recessed portion 26 registers with the lug 23 of the disk it is pushed from the disks 20 onto the disk 21, and unless the lug 23 of the disk 21 also registers with the recessed portion 26, the gear wheel 24 will ride on the disk 21 and further movement along the shaft 6 will be prevented. It will now mesh with the gear wheel 39 and movements of the wheel 45 will be communicated through the shaft 42 to the gear wheel 39 which will operate upon the gear wheel 24 to cause rotation of the disk 21 until its lug registers with the recessed portion 26, whereupon the arm 28 will slip the gear wheel 24 onto the disk 22. The gear wheel 40 will now operate upon the gear wheel 24 to cause rotation of the gear wheel 24 until its recessed por-

tion 26 registers with the lug 23 on the disk 22 which will occur upon a sufficient number of movements of the gear wheel 46 which is driven directly by the gear wheel 52. When 5 the gear wheel 24 passes the lug 23 of the disk 22 upon the dummy 34, the rod 31 engages the sector 61 and disconnects the shaft 29 from the lever 60. Further angular movements of the shaft 29 cannot be formed 10 by the lever 60. The stamping machine can no longer be operated to stamp mail until the machine has been reset. The machine is reset by bringing the disks 13, 14 and 15 to the zero line, that is, so as to cause the 15 zero to appear in the openings 12 of the plate 9, which places the lugs 23 of the disks 20, 21 and 22 in line, and upon a partial forward rotation of the gear wheel 24 its recessed portion 26 will be brought in line with 20 the lugs of the disks 20, 21 and 22, and then it may be shifted over the disks 20, 21 and 22, while at the same time the arm 28 may be pushed along the shaft 29 to a position that it may be engaged by the catch 36 and 25 held in this position until the gear wheel 24 is brought against the arm 28. When the gear wheel 24 has been placed in position one or more of the disks 13, 14 and 15 may be rotated as, for example, if the right to 30 stamp five pieces of mail is purchased from the postal authorities the disk 15 is rotated so that the numeral 5 will appear behind the plate 9; if twenty-five stamps, so to speak, are purchased, the disk 14 is also rotated so 35 that the numeral 2 appears behind the plate 9 and the friction between the sleeves 17 and 18 will also rotate the disk 15 the same angular distance; or if the user purchases the right to use the machine seven hundred 40 and twenty-five times, the disk 13 is rotated so that the numeral 7 appears behind the plate 9, and the other disks are rotated forward the same distance. This positions the lugs 23 of the disks 20, 21 and 22 in positions that correspond to, or are indicated by 45 the numerals of the disks 13, 14 and 15 as they appear behind the plate. Before the shaft 24 can slip by the lug 23 of the disk 20 the shaft 29 will have to be operated seven 50 hundred times, and then the shaft 29 will have to be operated twenty times before the gear wheel 24 will slip onto the disk 22. The shaft 29 will then have to be operated five times before the gear wheel 24 will slip 55 onto the dummy 34 and cause the sector 61 to disconnect the lever 60 from the shaft 29.

The mutilated Swiss gear wheel is provided with ten teeth, that is, the ten recesses into which the pin 83 (Fig. 5) enters and 60 produces ten step by step movements. The relation of the size of the gear wheels 52 and the gear wheel 46 is such that the shaft 29 will be operated ten times in order to cause a single complete rotation of the gear wheel 46. When the gear wheel 46 is rotated once 65

it causes a single step movement of the Swiss gear wheel 49, and consequently the gear wheel 46 has to be rotated ten times to produce a single rotation of the gear wheel 50. The pin wheel 47 which receives its movements from the gear wheel 49 must likewise be rotated ten times to form a complete rotation of the gear wheel 50. The movements of the gear wheel 50 is therefore one hundred times the movement of the gear 70 wheel 52, and the movements of the gear wheel 50 are communicated to the gear wheel 38. The gear wheel 52, in order to permit the gear wheel 24 to slide from the disk 20 and disconnect with the gear wheel 38 and 75 connect with the gear wheel 39, must be operated seven hundred times since the gear wheel 24 will not slide from the disk 20 until the Swiss gear wheel 50 has moved seven steps, or has been operated upon seven times 80 by the pin wheel 47. Connection now being established between the gear wheel 24 and the gear wheel 39, the gear wheel 52 will have to operate twenty times in order to cause the gear wheel 39 to rotate the gear 85 wheel 24 sufficient to cause it to slip by the disk 21. The gear wheel 24 will now be moved upon each operation of the shaft 29, an angular distance equal to the distance between two consecutive numbers on the disk 90 13, and when the shaft 29 has been operated five times the recess or opening 26 will register with the lug 23 on the disk 22, and the gear wheel 24 will slide upon the dummy 34, whereupon the rod 31 will disconnect the 100 clutch 61 from the lever 60 and further operations of the shaft 29 will be prevented until the mechanism has been reset.

I claim:

1. In a postage marking mechanism a plurality of independent operable stops, a marking mechanism, means operating according to the position of the stops for limiting the operations of the stamping mechanism to a predetermined number. 105

2. In a postage marking device a marking mechanism, gear wheels connected to the marking mechanism, a setting mechanism having limiting members, a gear wheel acted upon by the first named gear wheels in succession according to the position that the gear wheel is held by the limiting members. 115

3. In a postage marking device a marking mechanism, a plurality of gear wheels, means for causing the gear wheels to operate according to the operations of the marking mechanism in successive roots of 10, a gear wheel operated by the gear wheels, a setting mechanism for controlling the operations of the said marking mechanism through the 120 said gear wheels.

4. In a postage marking device a marking mechanism, a plurality of gear wheels operated step by step by the marking mechanism to produce revolution in the gear 130

- wheels in the ratio of consecutive powers of 10, a setting mechanism, a gear wheel interconnecting the gear wheels and the setting mechanism to connect the gear wheels 5 in succession with the said setting mechanism.
5. In a postage marking device a marking mechanism, gear wheels actuated by the marking mechanism in consecutive powers 10 of 10, a setting mechanism having a plurality of lugs and a gear wheel movable relative to the lugs and held in position by the lugs until rotated to predetermined points by the first named gear wheels.

6. In a postage marking device a marking 15 mechanism, gear wheels actuated by the marking mechanism in consecutive powers of 10, a setting mechanism having a plurality of lugs and a gear wheel movable relative to the lugs and held in position by the 20 lugs until rotated to predetermined points by the first named gear wheels, and means for preventing further operation of the marking device until the device has been reset.

In testimony whereof I have hereunto signed my name to this specification.

EDWARD M. McGOWAN.
